SPRINKLER HEAD

Arthur C. Rowley, Drexel Hill, Pa., assignor to
Globe Automatic Sprinkler Company, Philadelphia, Pa., a corporation of Pennsylvania

Application September 1, 1932. Serial No. 631,427

6 Claims. (Cl. 169—38)

My invention relates to improvements in automatic sprinkler fire-extinguishing systems, and more particularly relates to improvements in the sprinkler heads constituting important elements 5 of such systems.

The principal object of the invention is to provide a sprinkler head which shall have a relatively high efficiency in its intended function and which shall be further characterized by a relatively great durability.

To this general end, another object of my invention is to provide a sprinkler head in which the solder or other fusible agent is rendered substantially free from strain.

15 A still further object of the invention is to provide in a device of the stated character novel and improved means for supporting the load substantially exclusive of the fusible medium, said means being such as normally to assume a state 20 of substantial equilibrium, which state, however, is immediately and promptly destroyed upon fusion of the fusible agent.

The invention further resides in certain novel structural features and details hereinafter set 25 forth and illustrated in the attached drawing, in which:

Figures 1 and 2 are, respectively, side and front elevations of a sprinkler head made in accordance with my invention;

30 Fig. 3 is a view in perspective of an element of the device;

Fig. 4 is an exploded view in perspective of the inner and outer shell elements;

Fig. 5 is an end view of the ball and shell assembly, and

Fig. 6 is a section on the line 6—6, Fig. 5.

With reference to the drawing, a sprinkler head made in accordance with my invention may comprise the usual body member 1, this body member comprising a tubular portion 2 externally threaded at one end, and having at the other end a seat 3 for reception of a closure element 4. This closure element in the present instance is in the form of a disk having a hemispherical protrusion 5, see Fig. 3. From opposite sides and intermediate the ends of the portion 2 of the sprinkler head arms 6 and 7 extend transversely outwardly and upwardly, and join to form in effect a yoke. At the juncture of the 50 arms 6 and 7 is provided a threaded opening in alignment with the longitudinal axis of the tubular portion 2. This threaded opening is adapted to receive a screw 8 having a head 9 formed in well known manner to constitute a deflector for 55 water, as hereinafter set forth.

The portion 2 of the body 1 is adapted to be threaded into the distributor pipe of the sprinkler system, and means hereinafter described is provided for holding the cap 4 on its seat, thus sealing the opening through the portion 2 of the 60 sprinkler head. The cap-holding means is illustrated in Figs. 4 to 6, inclusive. This means comprises a plurality of spheres 11, which may be made of phosphor-bronze or other suitable material. In addition, I provide two sets of elements 12, 12 and 13, 13, which sets of elements are adapted respectively to form cylindrical casings. The casing formed of the elements 12, 12 is adapted to closely embrace the balls 11 with the latter arranged as shown in Fig. 6 in a single 70 row. The members 13, 13 are so proportioned as when assembled in longitudinal edge-to-edge relation to form a cylinder closely embracing the cylinder formed by the elements 12, 12. This is well shown in Figs. 5 and 6, and it will be 75 noted that the joints of the inner and outer shells are staggered. In assembly, the interstices between the balls 11 and the inner surface of the embracing cylinders 12, 12 are completely filled with solder or other suitable fastening 80 agent, and this solder also functions to hold together the elements 12, 12 of the inner cylinder around the balls. Similarly the elements 13, 13 of the outer cylinder are held together and upon the elements 12 by solder at the meeting edges 85 and on the inner faces thereof. Preferably, the diameter of the balls 11 is slightly less than the diameter of the cylinder formed by the elements 12, 12. A difference of .006 of an inch between 90 these two diameters will, for example, be found satisfactory. In this manner, while in assembly the balls are in substantially perfect alignment and, therefore, in substantial equilibrium, they are sufficiently misaligned to insure immediate separation under conditions hereinafter set 95 forth.

As shown in Figs. 1 and 2, the ball and cylinder assembly is interposed as a unit between the dome-like top of the cap 4 and the inner end of the screw 8, the screw being turned down upon the adjacent ball 11 so that the ball and cylinder assembly is placed under longitudinal compression. To hold the assembly in position, the top of the cap 4 and the lower end of the screw 8 may be slightly recessed or otherwise formed to prevent displacement of the balls 11 which they respectively engage. In view of the substantial alignment and consequent state of equilibrium of the balls 11, this compressive force has little tendency to squeeze the balls transversely upon the 110

cylinder shells 12, 12, so that practically none of the pressure is imposed upon the solder or other fusible material which binds the assembly together. Similarly the outer shell is maintained substantially free from pressures tending to separate this outer shell from the inner shell to which it is secured by solder or other fusible composition, as previously set forth.

While little force is required to maintain the balls in their substantially longitudinal alignment and stated equilibrium, it will be apparent that in view of the fact that the equilibrium is not complete, separation of the shells from the balls will immediately produce an unbalanced effect which will cause the balls to separate transversely one from the other, thereby releasing the closing pressure upon the cap 4 and permitting the pressure of the water or air within the system to throw this cap from the discharge port of the portion 2 of the sprinkler head. The water or other fluid rushing through this port is projected upon the concaved under side of the head 9 which functions to break up the stream and to distribute it more or less uniformly over the surrounding area. The greater the diameter of the inner cylindrical shell over and above the diameter of the balls 11, the less will be the equilibrium of the assembly, and the greater force will be applied to the solder or other fusible agent.

30 I claim:

1. A pressure-transmitting device for automatic sprinkler heads comprising a set of spherical elements, a cylindrical casing consisting of a plurality of longitudinal parts and within which said elements are retained in a substantially aligned series, a second cylindrical casing also consisting of a plurality of longitudinal parts and closely embracing the casing first named, and a fusible composition binding said elements and 35 casing parts into a unitary member.

2. In a temperature responsive device, a strut comprising a plurality of elements arranged in a row to form an inherently unstable series, an inner casing for said series comprising separable rigid members united by a fusible solder, and an outer casing embracing said inner casing and also comprising separable rigid members united by a fusible solder.

3. In a temperature responsive device, a strut comprising a plurality of elements arranged in a row to form an inherently unstable series, an inner casing for said series comprising separable rigid members united by a fusible solder, and an outer casing embracing said inner casing and also comprising separable rigid members united by a fusible solder, the soldered joints of said inner and outer casings being relatively staggered.

4. In a temperature responsive device, a strut comprising a plurality of elements arranged in a row to form an inherently unstable series, a casing for said series comprising separable rigid members united by a fusible solder, and a fusible compound in the interstices between the elements of said series and the casing and immobilizing the said elements in the casing.

5. In a temperature responsive device, a strut comprising a plurality of spheres arranged in a row to form an inherently unstable series, and a double-walled casing for said series, each wall comprising separable rigid members united by a fusible solder.

6. In a temperature responsive device, a strut comprising a plurality of spherical elements arranged in a row to form an inherently unstable series, a longitudinally split cylindrical casing the component members of which are united by a fusible solder, and a fusible composition substantially filling the interstices between the said spheres and the walls of the casing.
